(57) **ABSTRACT**

A light-emitting diode exposure head includes a lens array, a long holder to hold the lens array, and a substrate having light-emitting diodes that emit light to expose a photosensitive member. The lens array includes lenses and condenses the light emitted from the light-emitting diodes on the photosensitive member. The long holder includes a base portion having an opening into which the lens array is inserted, and a pair of extended portions extended in a direction that is opposite of an emitting direction of the light along an optical axis of each of the lenses from both ends of the base portion in a transverse direction of the long holder. The pair of extended portions and the substrate are bonded in a state where leading edges of the pair of extended portions are in contact with a light-emitting surface of the substrate that serves as a surface of the substrate.

EXPOSURE HEAD**

BACKGROUND

Field

The present disclosure relates to a light-emitting diode (LED) exposure head that exposes a photosensitive member to light emitted from LEDs, and an image forming apparatus including the LED exposure head.

Description of the Related Art

Some image forming apparatuses, such as a printer and a copying machine, include a light-emitting diode (LED) exposure head. The LED exposure head includes a plurality of LEDs, and a photosensitive member, such as a photosensitive drum, is exposed to light emitted from the plurality of LEDs. Some light sources for emitting light use an organic electroluminescence (EL). The organic EL is also called an organic light-emitting diode (OLED). The plurality of LEDs is arranged on a substrate, and the light emitted from the plurality of LEDs is condensed on the photosensitive member by a lens array.

Japanese Patent Application Laid-Open No. 2019-1103 discusses a holder that holds a substrate and a lens array. The holder includes a base portion having an opening into which the lens array is inserted, and a pair of extended portions extended in a transverse direction of the base portion from both ends of the base portion. In the holder, the base portion and the pair of extended portions form a U-shape. The substrate and the pair of extended portions are bonded with an adhesive in a state where the substrate is fit in a gap between the pair of extended portions.

However, in the configuration in which the substrate is held in the inside of the pair of extended portions, as in the LED exposure head discussed in Japanese Patent Application Laid-Open No. 2019-1103, there is a need to set a width between the pair of extended portions to be greater than the width of the substrate. Accordingly, the width of the holder is increased, which may lead to an increase in the size of each of the LED exposure head and the image forming apparatus in the width direction.

SUMMARY

According to an aspect of the present disclosure, a light-emitting diode exposure head includes a substrate including a plurality of light-emitting diodes configured to emit light to expose a photosensitive member, a lens array including a plurality of lenses and configured to condense the light emitted from the plurality of light-emitting diodes on the photosensitive member, and a long holder configured to hold the lens array, wherein the long holder includes a base portion having an opening into which the lens array is inserted, and a pair of extended portions extended in a direction that is opposite of an emitting direction of the light along an optical axis of each of the plurality of lenses from both ends of the base portion in a transverse direction of the long holder, and wherein the pair of extended portions and the substrate are bonded in a state where leading edges of the pair of extended portions are in contact with a light-emitting surface of the substrate that serves as a surface of the substrate.

Further features of the present disclosure will become apparent from the following description of exemplary embodiments with reference to the attached drawings.

5 BRIEF DESCRIPTION OF THE DRAWINGS

FIGS. 1A and 1B are schematic sectional views of an image forming apparatus.

10 FIGS. 2A and 2B are views each illustrating a configuration in the vicinity of drum units.

FIG. 3 is a schematic perspective view of a light-emitting diode (LED) exposure head.

15 FIGS. 4A to 4D are schematic views illustrating an example of a sectional shape of a holding member.

FIGS. 5A, 5B1, and 5B2 illustrate a substrate, and FIGS. 16 5C1 and 5C2 illustrate a lens array.

FIG. 6 is a diagram illustrating the substrate including an organic light-emitting diode (OLED).

20 FIGS. 7A, 7B, and 7C are diagrams each illustrating an internal structure of the substrate including the OLED.

FIGS. 8A and 8B are diagrams each illustrating a light-emitting surface and a mounting surface of the substrate.

25 FIG. 9 is a diagram illustrating a conventional LED exposure head.

FIGS. 10A, 10B, and 10C are diagrams each illustrating a configuration for mounting the holding member and the substrate according to a first exemplary embodiment.

30 FIGS. 11A, 11B, and 11C are views each illustrating protrusions that contact the substrate and are provided on the holding member according to the first exemplary embodiment.

FIG. 12 is a diagram illustrating a configuration for mounting the holding member and the substrate according to a second exemplary embodiment.

35 FIG. 13 is a view illustrating protrusions that contact the substrate and are provided on the holding member according to the second exemplary embodiment.

DESCRIPTION OF THE EMBODIMENTS

40 Modes for carrying out the present disclosure will be described below with reference to the accompanying drawings. Unless otherwise explicitly stated, the dimensions, materials, shapes, relative positions, and the like of components described below are not intended to limit the scope of the present disclosure.

(Image Forming Apparatus)

45 A first exemplary embodiment of the present disclosure will be described below. A schematic configuration of an image forming apparatus 1 will now be described. FIG. 1A is a schematic sectional view of the image forming apparatus 1. The image forming apparatus 1 illustrated in FIG. 1A is a color printer (single function printer (SFP)) including no reading device, but instead may be a copying machine including a reading device. The present exemplary embodiment is not limited to a color image forming apparatus including a plurality of photosensitive drums 103 as illustrated in FIG. 1A, but instead may be a color image forming apparatus including a single photosensitive drum 103, or an image forming apparatus that forms a black-and-white image.

55 The image forming apparatus 1 illustrated in FIG. 1A includes four image forming units 102Y, 102M, 102C, and 102K (hereinafter also collectively referred to as an “image forming unit 102”) that form toner images of respective colors of yellow, magenta, cyan, and black. The image forming units 102Y, 102M, 102C, and 102K include pho-

tosensitive drums **103Y**, **103M**, **103C**, and **103K** (hereinafter also collectively referred to as a “photosensitive drum **103**”), respectively, which are examples of a photosensitive member. The photosensitive drum **103** may be a photosensitive belt. The image forming units **102Y**, **102M**, **102C**, and **102K** include chargers **104Y**, **104M**, **104C**, and **104K** (hereinafter also collectively referred to as a “charger **104**”), respectively, as charging units that charge the photosensitive drums **103Y**, **103M**, **103C**, and **103K**, respectively. The image forming units **102Y**, **102M**, **102C**, and **102K** include light-emitting diode (LED) exposure units **520Y**, **520M**, **520C**, and **520K** (hereinafter also collectively referred to as an “exposure unit **520**”), respectively, as exposure light sources that expose the photosensitive drums **103Y**, **103M**, **103C**, and **103K**, respectively, to light. Further, the image forming units **102Y**, **102M**, **102C**, and **102K** include developing devices **106Y**, **106M**, **106C**, and **106K** (hereinafter also collectively referred to as a “developing device **106**”), respectively, as developing units that develop an electrostatic latent image on the photosensitive drum **103** with toner and develop the toner image of the corresponding color on the photosensitive drum **103**. Symbols Y, M, C, and K represent yellow, magenta, cyan, and black colors of toner, respectively.

The image forming apparatus **1** illustrated in FIG. 1A is an image forming apparatus that adopts a “lower surface exposure method” for exposing the photosensitive drum **103** to light from below. The following description will be provided on the premise that the image forming apparatus **1** adopts the lower surface exposure method. However, the image forming apparatus **1** may adopt an “upper surface exposure method” for exposing the photosensitive drums **103** to light from above, like an image forming apparatus **2** illustrated in FIG. 1B. In FIG. 1B, portions that present the same configurations as those in FIG. 1A are denoted by the same reference symbols.

The image forming apparatus **1** includes an intermediate transfer belt **107** onto which the toner images formed on the photosensitive drum **103** are transferred, and primary transfer rollers **108** (Y, M, C, and K) that sequentially transfer the toner images formed on the photosensitive drum **103** to the intermediate transfer belt **107**. Further, the image forming apparatus **1** includes a secondary transfer roller **109** that serves as a transfer unit and transfers the toner images on the intermediate transfer belt **107** onto a sheet of recording paper **P** conveyed from a sheet feeding unit **101**, and a fixing device **100** that fixes the secondarily transferred images onto the recording paper **P**. Not only the intermediate transfer method using the intermediate transfer belt **107** as described above, but also a direct transfer method for directly transferring images onto a sheet from the photosensitive drum **103** may be used.

(Image Forming Process)

The surface of the photosensitive drum **103Y** charged by the charger **104Y** is exposed to light by the exposure unit **520Y**. As a result, an electrostatic latent image is formed on the surface of the photosensitive drum **103Y**. Next, the developing device **106Y** develops the electrostatic latent image formed on the surface of the photosensitive drum **103Y** with yellow toner. The yellow toner image developed on the surface of the photosensitive drum **103Y** is transferred onto the intermediate transfer belt **107** by the primary transfer roller **108Y**. Magenta, cyan, and black toner images are also transferred onto the intermediate transfer belt **107** through a similar image forming process.

The toner color images of the respective colors transferred onto the intermediate transfer belt **107** are conveyed to a

secondary transfer portion **T2** by the intermediate transfer belt **107**. A transfer bias for transferring the toner images onto the recording paper **P** is applied to the secondary transfer roller **109** that is disposed at the secondary transfer portion **T2**. The transfer bias applied to the secondary transfer roller **109** causes the toner images conveyed to the secondary transfer portion **T2** to be transferred onto the recording paper **P** conveyed from the sheet feeding unit **101**. The recording paper **P** onto which the toner images are transferred is conveyed to the fixing device **100**. The fixing device **100** fixes the toner images onto the recording paper **P** with heat and pressure. The recording paper **P** on which the fixation process has been performed by the fixing device **100** is discharged onto a sheet discharge portion **111**.

(Drum Unit and Developing Unit)

Drum units **518Y**, **518M**, **518C**, and **518K** (hereinafter also collectively referred to as a “drum unit **518**”) including the photosensitive drum **103Y**, **103M**, **103C**, and **103K**, respectively, are mounted on the image forming apparatus **1**. The drum unit **518** is a cartridge that is replaced by an operator, such as a user or maintenance personnel. The drum unit **518** rotatably supports the photosensitive drum **103**. In this case, the drum unit **518** also functions as a drum support member that rotatably supports the photosensitive drum **103**. In the present exemplary embodiment, the drum unit including the drum support member is referred to as the drum unit **518**. Specifically, the photosensitive drum **103** is rotatably supported by a frame of the drum unit **518**. The drum unit **518** need not necessarily include the charger **104** and a cleaning device.

Developing units **641Y**, **641M**, **641C**, and **641K** (hereinafter also collectively referred to as a “developing unit **641**”) are mounted on the image forming apparatus **1** according to the present exemplary embodiment as members separate from the drum unit **518**. The developing unit **641** according to the present exemplary embodiment is a cartridge having a configuration in which the developing device **106** illustrated in FIG. 1A and a toner storage portion are integrated. The developing device **106** includes a developing sleeve (not illustrated) that carries developer. The developing unit **641** is provided with a plurality of gears that rotate a screw for mixing the toner and carrier. For example, when the gears have degraded with time, the operator detaches the developing unit **641** from an apparatus body of the image forming apparatus **1** and replaces the developing unit **641**. Each of the drum unit **518** and the developing unit **641** according to the present exemplary embodiment may be a process cartridge having a configuration in which the drum unit **518** and the developing unit **641** described above are integrated.

FIG. 2A is a perspective view illustrating a schematic structure in the vicinity of the drum units **518** (Y, M, C, K) and the developing units **641** (Y, M, C, K) included in the image forming apparatus **1**. FIG. 2B is a view illustrating a state where the drum units **518** are inserted into the image forming apparatus **1** from the outside of the apparatus body.

As illustrated in FIG. 2A, the image forming apparatus **1** includes a front side plate **642** that is formed of a plate, and a back side plate **643** that is also formed of a plate. The front side plate **642** is a side wall provided on the front side of the image forming apparatus **1**. The front side plate **642** constitutes a part of a housing of the apparatus body on the front side of the apparatus body of the image forming apparatus **1**. The back side plate **643** is a side wall provided on the back side of the image forming apparatus **1**. The back side plate **643** constitutes a part of the housing of the apparatus body on the back side of the main body of the image forming

apparatus 1. As illustrated in FIG. 2A, the front side plate 642 and the back side plate 643 are arranged to be opposed to each other, and a plate (not illustrated) serving as a beam is bridged over the front side plate 642 and the back side plate 643. The front side plate 642, the back side plate 643, and the beam (not illustrated) constitute a part of the frame of the image forming apparatus 1. The term "front surface side" or "front side" of the image forming apparatus 1 or the components thereof according to the present exemplary embodiment refers to a side where the drum unit 518 is inserted into or removed from the apparatus body.

The front side plate 642 is provided with an opening into which the drum unit 518 and the developing unit 641 can be inserted into or removed from, on the front side of the image forming apparatus 1. The drum unit 518 and the developing unit 641 are mounted at predetermined positions (mounting positions) in the apparatus body of the image forming apparatus 1 through the opening. The image forming apparatus 1 includes covers 558Y, 558M, 558C, and 558K (hereinafter also collectively referred to as a "cover 558") that cover the front side of each of the drum unit 518 and the developing unit 641 that are mounted at the mounting positions. One end of the cover 558 is fixed to the apparatus body of the image forming apparatus 1 with a hinge. The hinge enables the cover 558 to pivot relative to the main body of the image forming apparatus 1. The operator completes the replacing work by opening the cover 558 and taking out the drum unit 518 or the developing unit 641 from the main body, and by inserting a new drum unit 518 or a new developing unit 641 and closing the cover 558.

As illustrated in FIGS. 2A and 2B, a side where the front side plate 642 is located is hereinafter defined as the front side (or the front surface side) of the apparatus body, and a side where the back side plate 643 is located is hereinafter defined as the back side (or the back surface side) of the apparatus body. With reference to the photosensitive drum 103K on which the electrostatic latent image for the black toner image is formed, a side where the photosensitive drum 103Y on which the electrostatic latent image for the yellow toner image is formed is disposed is defined as a right side. With reference to the photosensitive drum 103Y on which the electrostatic latent image for the yellow toner image is formed, a side where the photosensitive drum 103K on which the electrostatic latent image for the black toner image is formed is disposed is defined as a left side. A direction that is perpendicular to the front-back direction and left-right direction defined herein and that is a vertically upward direction is defined as an up direction, and a direction that is perpendicular to the front-back direction and left-right direction defined herein and that is a vertically downward direction is defined as a down direction. The front direction, the back direction, the right direction, the left direction, the up direction, and the down direction, which are defined above, are illustrated in FIG. 2B. The term "rotational axis direction" of the photosensitive drum 103 used herein refers to a direction that coincides with the front-back direction illustrated in FIG. 2B. The term "longitudinal direction" of a LED print head (which is an example of a LED exposure head) 105 also refers to the direction that coincides with the front-back direction illustrated in FIG. 2B. In other words, the rotational axis direction of the photosensitive drum 103 and the longitudinal direction of the LED print head 105 coincide with each other.

(Exposure Unit)

Next, the exposure unit 520 including the LED print head 105 will be described. The LED print head 105 has an elongated shape extending in the rotational axis direction of

the photosensitive drum 103. The LED print head 105 includes a holding member 505 (which is an example of a holder), a lens array 506, and a substrate (not illustrated). The lens array 506 and the substrate are held by the holding member 505. In the present exemplary embodiment, the holding member 505 is made of metal and is formed by bending a plate material obtained by performing a plating process on a galvanized steel plate or cold-rolled steel plate into a U-shape. However, the holding member 505 is not limited to a member made of metal, but instead may be a member made of resin. An example of an exposure method adopted for an electrophotographic image forming apparatus is a laser beam scanning exposure method for performing scanning with an irradiation beam from a semiconductor laser using a polygon mirror or the like to expose the surface of the photosensitive drum to light through an f-O lens or the like. The "LED print head 105" described in the present exemplary embodiment is used for a LED exposure method for exposing the surface of the photosensitive drum 103 to light using light-emitting elements, such as LEDs, that are arranged along the rotational axis direction of the photosensitive drum 103, and is not used for the above-described laser beam scanning exposure method.

The exposure unit 520 described in the present exemplary embodiment is provided on the lower side in the vertical direction relative to the rotational axis of the photosensitive drum 103. LEDs serving as light-emitting elements are provided on the substrate (not illustrated) included in the holding member 505, and these light-emitting elements expose the surface of the photosensitive drum 103 to light from below. However, the exposure unit 520 may be provided on the upper side in the vertical direction relative to the rotational axis of the photosensitive drum 103 and may expose the surface of the photosensitive drum 103 to light from above (see FIG. 1B). FIG. 3 is a schematic perspective view illustrating the exposure unit 520 included in the image forming apparatus 1 according to the present exemplary embodiment.

As illustrated in FIG. 3, the exposure unit 520 includes the LED print head 105, a support member 526, a first link mechanism 530, and a second link mechanism 540.

As illustrated in FIG. 3, the holding member 505 of the LED print head 105 is provided with a contact pin 514 and a contact pin 515. The contact pin 514 and the contact pin 515 are examples of a pin made of metal. For example, the contact pin 515 is provided on the holding member 505 on one side (back side) of the lens array 506 in the rotational axis direction of the photosensitive drum 103, and the contact pin 515 projects from both sides of the holding member 505 in the optical axis direction of the lens array 506. The contact pin 514 has a configuration similar to that of the contact pin 515. When the contact pin 514 and the contact pin 515 are brought into contact with the drum unit 518, a gap is formed between the lens array 506 and the photosensitive drum 103. Thus, the position of the LED print head 105 relative to the photosensitive drum 103 is determined. In the present exemplary embodiment, the contact pin 514 and the contact pin 515 are straight pins made of metal. The contact pin 514 and the contact pin 515 are fixed to the holding member 505, which is made of metal, by welding. Thus, in the present exemplary embodiment, the contact pin 514 and the contact pin 515 are integrally formed with the holding member 505.

The first link mechanism 530 includes a link member 535 and a link member 536. The second link mechanism 540 includes a link member 537 and a link member 538. As described in detail below, the link member 535 is attached

to the back side relatively to the center of the holding member **505** in the rotational axis direction of the photosensitive drum **103**, and the link member **537** is attached to the front side relatively to the center of the holding member **505** in the rotational axis direction of the photosensitive drum **103**.

A slide member **525** is slidably moved in the front-back direction along with an opening/closing operation of the cover **558** provided on the front side of the image forming apparatus **1**. The link members **535** to **538** are rotated along with the slidable movement of the slide member **525**, thus enabling the LED print head **105** to move in the up-down direction.

In the present exemplary embodiment, the LED print head **105** is provided on the lower side in the vertical direction relatively to the photosensitive drum **103**. In other words, in the image forming apparatus **1** according to the present exemplary embodiment, the LED print head **105** exposes the surface of the photosensitive drum **103** to light from below in the vertical direction.

As illustrated in FIG. 3, the exposure unit **520** includes the support member **526**. The support member **526** supports the LED print head **105** via the first link mechanism **530** and the second link mechanism **540**. Specifically, the link member **535** of the first link mechanism **530** supports the holding member **505**, and the link member **537** of the second link mechanism **540** supports the holding member **505**.

The support member **526** is formed by bending a plate into a U-shape. The support member **526** is a member having a longitudinal shape extending in the rotational axis direction of the photosensitive drum **103**. One end (front side) of the support member **526** in the longitudinal direction of the support member **526** is fixed to the front side plate **642**, and the other end (back side) of the support member **526** in the longitudinal direction of the support member **526** is fixed to the back side plate **643**. Thus, the position of the support member **526** with respect to the photosensitive drum **103** is fixed on the side that is opposite to the side where the photosensitive drum **103** is disposed with respect to the holding member **505**.

The support member **526** includes the slide member **525** that is movable in the longitudinal direction of the support member **526**. Along with the movement of the slide member **525** relative to the support member **526**, the link members **535** to **538** are rotated, thus moving the LED print head **105** relatively to the support member **526**.

FIGS. 4A to 4D are schematic views each illustrating a section of the holding member **505** illustrated in FIG. 3 when the section is taken along a plane S illustrated in FIG. 3. An example of a portion to be cut when a sectional shape is considered is a plane that passes through the lens array **506** and is vertical to the longitudinal direction of the holding member **505**. A section of the holding member **505** according to the present exemplary embodiment has a shape illustrated in FIG. 4A, but instead may have, for example, shapes as illustrated in FIGS. 4B to 4D. As described above, the holding member **505** has a U-shape. Specifically, the holding member **505** may have such a shape that a pair of extended portions **5050R** and **5050L** is curved as illustrated in FIG. 4B, or such a shape that each of the pair of extended portions **5050R** and **5050L** has a step shape as illustrated in FIGS. 4C and 4D, as long as the pair of extended portions **5050R** and **5050L** is extended from, respectively, the right and left ends of a base portion **5050B** that holds the lens array **506**.

(Substrate and Lens Array)

Next, a substrate **502** and the lens array **506**, which are held by the holding member **505**, will be described with reference to FIGS. 5A, 5B1, 5B2, 5C1, and 5C2. First, the substrate **502** will be described. FIG. 5A is a schematic perspective view of the substrate **502**. FIG. 5B1 illustrates an array of a plurality of LEDs **639** provided on the substrate **502**. FIG. 5B2 is an enlarged view of FIG. 5B1.

LED chips **639** are mounted on the substrate **502**. As illustrated in FIG. 5A, the LED chips **639** are provided on one surface of the substrate **502**, and a connector **504** is provided on the back side of the substrate **502**. The term “one surface” used herein, or the surface on which the LED chips **639** are provided, is defined as a “light-emitting surface”. In other words, one of the front and back surfaces of the substrate **502** from which light is emitted to the photosensitive drum **103** corresponds to the light-emitting surface. The substrate **502** is provided with wiring for supplying a signal to each LED chip **639**. The connector **504** is connected to one end of a flexible flat cable (FFC) (not illustrated). The substrate **502** includes a control portion and a connector. The other end of the FFC is connected to the connector. A control signal is input to the substrate **502** from the control portion in the apparatus body of the image forming apparatus **1** through the FFC and the connector **504**. Each LED chip **639** is driven by the control signal input to the substrate **502**.

Each LED chip **639** mounted on the substrate **502** will be described in more detail. As illustrated in FIGS. 5B1 and 5B2, a plurality of (29) LED chips **639-1** to **639-29** on which the plurality of LEDs **503** is arranged is arranged on one surface of the substrate **502**. On each of the LED chips **639-1** to **639-29**, a row of 516 LEDs is arranged in the longitudinal direction of each LED chip. A center-to-center distance **k2** between LEDs that are adjacent to each other in the longitudinal direction of each LED chip **639** corresponds to a resolution of the image forming apparatus **1**. The resolution of the image forming apparatus **1** according to the present exemplary embodiment is 1200 dpi. Accordingly, the LED chips **639-1** to **639-29** are arranged in a row in the longitudinal direction of each LED chip **639** with a center-to-center distance between adjacent LEDs of 21.16 μm . Therefore, the LED print head **105** according to the present exemplary embodiment has an exposure range of about 316 mm. A photosensitive layer of the photosensitive drum **103** is formed with a width of 316 mm or more. Since the length of a long side of a sheet of A4-sized recording paper and the length of a short side of a sheet of A3-sized recording paper are 297 mm, the LED print head **105** according to the present exemplary embodiment has the exposure range that enables image formation on A4-sized recording paper and A3-sized recording paper.

The LED chips **639-1** to **639-29** are arranged alternately in two rows along the rotational axis direction of the photosensitive drum **103**. In other words, as illustrated in FIG. 5B1, the odd-numbered LED chips **639-1**, **639-3**, . . . , and **639-29** when counted from the left side are mounted in one row in the longitudinal direction of the substrate **502**, and the even-numbered LED chips **639-2**, **639-4**, . . . , and **639-28** are mounted in one row in the longitudinal direction of the substrate **502**. By arranging the LED chips **639** in such a manner, a center-to-center dimension **k1** between a LED arranged at one end of one of different LED chips **639** arranged adjacent to each other in the longitudinal direction of the LED chip **639** and an LED arranged at the other end of the other one of the different LED chips **639** arranged adjacent to each other can be set to

be equal to the center-to-center dimension k_2 between adjacent LEDs on a single LED chip **639**, as illustrated in FIG. 5B2.

In the present exemplary embodiment, the light-emitting elements are semiconductor LEDs that are light-emitting diodes, but instead may be, for example, organic light-emitting diodes (OLEDs). Each OLED is also called an organic electroluminescence (EL) and is a current-driven light-emitting element. The OLEDs are arranged, for example, on a line along a main scanning direction (rotational axis direction of the photosensitive drum **103**) on a thin film transistor (TFT) substrate, and are electrically connected in parallel with a power supply wire that is also provided along the main scanning direction.

Next, the lens array **506** will be described. FIG. 5C1 is a schematic view of the lens array **506** as viewed from the side where the photosensitive drum **103** is located. FIG. 5C2 is a schematic perspective view of the lens array **506**. As illustrated in FIG. 5C1, a plurality of lenses is arranged in two rows along the array direction of the plurality of LEDs **503**. The lenses are arranged alternately so that one of lenses in a row is arranged to contact both of adjacent lenses in the array direction of lenses in the other row. Each lens is a columnar rod lens made of glass, and includes an incoming surface into which the light emitted from each LED **503** enters and an outgoing surface through which the light entering from the incoming surface exits. The material of each lens is not limited to glass, but instead may be, for example, plastic. The shape of each lens is not limited to a columnar shape. For example, each lens may have a polygonal prism shape such as a hexagonal cylindrical shape.

A broken line Z illustrated in FIG. 5C2 represents an optical axis of a lens. The LED print head **105** is moved by a moving mechanism **640** substantially in the direction of the optical axis of the lens indicated by the broken line Z . The term "optical axis" of the lens described herein refers to a line that connects the center of the light-emitting surface of the lens and the focal point of the lens. Since the lens array **506** includes a plurality of lenses, there is a plurality of "lens optical axes". However, these optical axes are substantially parallel to each other. Accordingly, when the "lens optical axis" in the lens array **506** is defined, any one of the plurality of lenses included in the lens array **506** may be selected and the optical axis of the selected lens may be defined as the lens optical axis. The lens array **506** functions to condense the light emitted from each LED **503** on the surface of the photosensitive drum **103**.

The plurality of LEDs **503** and the lens array **506** provided on the substrate **502** described above are held by the holding member **505** in such a manner that the LEDs **503** and the lens array **506** are opposed to each other. Thus, the light emitted from the plurality of LEDs **503** is condensed on the surface of the photosensitive drum **103** by the lens array **506**. In the present exemplary embodiment, the light emitted from three LEDs **503** (plurality of LEDs **503**) can pass through a single lens. Moreover, light emitted from a single LED **503** travels radially, and thus the light can pass through a plurality of lenses. In other words, the light emitted from the plurality of LEDs **503** passes through the lens array **506** (some of the plurality of lenses included in the lens array **506**) and exposes the photosensitive drum **103**.

An OLED may be used as a light source that emits light to expose the photosensitive drum **103**. A substrate using an OLED as a light source will be described with reference to FIG. 6 and FIGS. 7A to 7C.

FIG. 6 is a diagram illustrating the substrate **502** when the OLED is used as each light-emitting element. FIG. 6 illus-

trates an internal configuration of the substrate **502**. As illustrated in FIG. 6, the longitudinal direction of the substrate **502** is defined as an X-direction and the transverse direction of the substrate **502** is defined as a Y-direction. The Y-direction can also be referred to as a rotational direction of the photosensitive drum **103**, or a movement direction of the photosensitive surface (photosensitive member surface) of the rotating photosensitive drum **103**. The X-direction is substantially orthogonal to the Y-direction or the rotational direction of the photosensitive drum **103**. In other words, the X-direction is substantially parallel to the rotational axis direction of the photosensitive drum **103**. The "substantially orthogonal" direction allows an inclination of about $\pm 1^\circ$ with respect to an angle of 90° , and the "substantially parallel" direction allows an inclination of about $\pm 1^\circ$ based on an angle of 0° formed between the directions. Specifically, the longitudinal direction of the substrate **502** may be inclined by about $\pm 1^\circ$ with respect to the rotational axis direction of the photosensitive drum **103**. The transverse direction of the substrate **502** may be inclined by about $\pm 1^\circ$ with respect to the rotational direction of the photosensitive drum **103**. The substrate **502** has a configuration in which wire bonding pads (hereinafter referred to as WB pads) **601-1**, **601-2**, **601-3**, and **601-4** are formed on a silicon substrate **402**. The silicon substrate **402** incorporates a circuit portion **602** (as indicated by a broken line). As the circuit portion **602**, an analog drive circuit, a digital control circuit, or a configuration including both of the analog drive circuit and the digital control circuit can be used. Power supply to the circuit portion **602** and input/output of signals or the like from the outside of the exposure unit **520** are carried out through the WB pads **601-1** to **601-4**.

The substrate **502** including the OLED includes a line-shaped light-emitting region **604** extending along the rotational axis direction of the photosensitive drum **103**. The light-emitting region **604** includes an anode, a cathode, and a light-emitting layer **450** (see FIGS. 7A and 7B) to be described below. The light-emitting region **604** is a region where light is emitted when a potential difference is generated between the anode and the cathode.

The circuit portion **602** is provided with a drive portion that drives the light-emitting region **604** and a data transfer/light-emitting signal generation portion that generates a signal for causing the light-emitting region **604** to emit light (the signal is hereinafter referred to as a light-emitting signal). The circuit portion **602** is formed on the silicon substrate **402**. Thus, the circuit that enables high-speed processing can be formed.

The substrate **502** having the OLED will be described in more detail with reference to FIGS. 7A to 7C. The X-direction illustrated in FIGS. 7A to 7C indicates the longitudinal direction of the exposure head **105**. A Z-direction is a direction in which layers of a layer structure to be described below are stacked (stacking direction). FIG. 7A is an enlarged view illustrating a major part of the schematic view of a section taken along a line A-A in FIG. 6. FIG. 7A is a schematic view of lower electrodes **410-1** to **410-748** to be described below as viewed in the Y-direction. As illustrated in FIGS. 7A and 7B, the substrate **502** includes the silicon substrate **402**, the lower electrodes **410-1** to **410-748**, the light-emitting layer **450**, and an upper electrode **460**. The silicon substrate **402** is a drive substrate on which a drive circuit including drive portions corresponding to the respective lower electrodes **410-1** to **410-748** to be described below is formed in a manufacturing process.

As illustrated in FIGS. 7A and 7B, the lower electrodes **410-1** to **410-748** (cathodes) are a plurality of electrodes

formed on the silicon substrate 402 as a layer (first electrode layer). The lower electrodes 410-1 to 410-748 are formed on a plurality of drive portions incorporated in the silicon substrate 402 through a manufacturing process of manufacturing the silicon substrate 402 and by using an Si integrated circuit processing technique. The lower electrodes 410-1 to 410-748 may be desirably made of metal having a high reflectance with respect to the emission wavelength of the light-emitting layer 450 to be described below. Accordingly, the lower electrodes 410-1 to 410-748 may desirably contain argentum (Ag), aluminum (Al), or an alloy of these materials, or an alloy of silver and magnesium.

As illustrated in FIG. 7C, the lower electrodes 410-1 to 410-748 are provided in correspondence with respective pixels in the X-direction. In other words, each of the lower electrodes 410-1 to 410-748 is provided to form a pixel. The lower electrodes 410-1 to 410-748 form a first electrode row. The lower electrodes 410-1 to 410-748 that form the first electrode row are arranged in the rotational axis direction of the photosensitive drum 103. In this case, the lower electrodes 410-1 to 410-748 may be arranged with an inclination of about $\pm 1^\circ$ with respect to the rotational axis direction of the photosensitive drum 103. The lower electrodes 410-1 to 410-748 need not necessarily be arranged in parallel to the rotational axis direction of the photosensitive drum 103.

A width W of each of the lower electrodes 410-1 to 410-748 in the X-direction is a width corresponding to a width of one pixel. An interval d is a distance between lower electrodes in the X-direction (array interval). Adjacent ones of the lower electrodes 410-1 to 410-748 are formed at the interval d on the silicon substrate 402. A plurality of drive units formed on the silicon substrate 402 can individually control voltages of the lower electrodes 410-1 to 410-748. The organic material of the light-emitting layer 450 is filled in the interval d, and the lower electrodes 410-1 to 410-748 are partitioned by the organic material.

The shape of each lower electrode 410 is not limited to a square shape, but instead may be any shape, such as a polygonal shape with four or more sides, a circular shape, or an elliptical shape, as long as light with a sufficiently high intensity for the size of the exposure region corresponding to the output resolution of the image forming apparatus can be emitted and the image quality of an output image obtained by the light satisfies the design specifications of the image forming apparatus.

Next, the light-emitting layer 450 will be described. The light-emitting layer 450 is stacked and formed on the silicon substrate 402 on which the lower electrodes 410-1 to 410-748 are formed. Specifically, in a portion where the lower electrodes 410-1 to 410-748 are formed, the light-emitting layer 450 is stacked on the lower electrodes 410-1 to 410-748. In a portion where the lower electrodes 410-1 to 410-748 are not formed, the light-emitting layer 450 is stacked on the silicon substrate 402. The present exemplary embodiment illustrates an example where the light-emitting layer 450 is formed across the lower electrodes 410-1 to 410-748 in the light-emitting device 401. However, the present exemplary embodiment is not limited to this example. For example, as in the lower electrodes 410-1 to 410-748, the light-emitting layer 450 may be stacked and formed separately on the respective lower electrodes, or the lower electrodes 410-1 to 410-748 may be divided into a plurality of groups and a single light-emitting layer may be stacked on the lower electrode belonging to the corresponding one of the divided groups.

For example, an organic material can be used for the light-emitting layer 450. The light-emitting layer 450 serv-

ing as an organic EL film has a laminate structure including function layers, such as an electron transport layer, a hole transport layer, an electron-injection layer, a hole-injection layer, an electron block layer, and a hole block layer. Not only an organic material, but also an inorganic material may be used for the light-emitting layer 450.

The upper electrode 460 (anode) is stacked (as a second electrode layer) on the light-emitting layer 450. The upper electrode 460 is an electrode that enables light with the emission wavelength of the light-emitting layer 450 to be transmitted. Accordingly, in the upper electrode 460 used in this example, a material containing Indium Tin Oxide (ITO) is used as a transparent electrode. An electrode made of ITO has a transmittance of 80% or more with respect to light in a visible light region, and thus the electrode is suitably used as an organic EL electrode.

The upper electrode 460 is formed on the opposite side of the lower electrodes 410-1 to 410-748 with at least the light-emitting layer 450 interposed therebetween. Specifically, in the Z-direction, the light-emitting layer 450 is disposed between the upper electrode 460 and the lower electrodes 410-1 to 410-748, and the region in which the lower electrodes 410-1 to 410-748 are formed is included in the region in which the upper electrode 460 is formed when the lower electrodes 410-1 to 410-748 are projected on the upper electrode 460 in the Z-direction. The transparent electrode need not necessarily be stacked on the entire light-emitting layer 450. However, in order to effectively emit the light generated in the light-emitting layer 450 to the outside of the light-emitting device 401, the occupied area of the upper electrode 460 may be preferably 100% or more, and more preferably, 120% or more with respect to the occupied area of one pixel. An upper limit of the occupied area of the upper electrode 460 can be optionally designed depending on the area of the silicon substrate 402 and the area of the light-emitting layer 450. Wiring may be provided in a portion other than the portion where light is transmitted in the upper electrode 460.

The drive circuit controls the potentials of the lower electrodes 410-1 to 410-748 based on image data so that a potential difference can be generated between the upper electrode 460 and any one of the lower electrodes 410-1 to 410-748.

An example of the substrate 502 including the OLED as described above is a top-emission-type light-emitting device. When a voltage is applied to the upper electrode 460 serving as the anode and to each lower electrode 410 serving as the cathode and a potential difference is generated between these electrodes, electrons flow into the light-emitting layer 450 from the cathode and holes flow into the light-emitting layer 450 from the anode. In the light-emitting layer 450, electrons and holes are recombined, so that the light-emitting layer 450 emits light. When the light-emitting layer 450 emits light, the light directed toward the upper electrode 460 is transmitted through the upper electrode 460 and is emitted in a direction indicated by an arrow A illustrated in FIGS. 7A and 7B from the light-emitting device 401. The light directed toward each lower electrode 410 from the light-emitting layer 450 is reflected toward the upper electrode 460 by each lower electrode 410, and the reflected light is also transmitted through the upper electrode 460 and is emitted from the light-emitting device 401. There is a time difference between a timing when light is directly emitted from the light-emitting layer 450 to the upper electrode 460 and a timing when light is reflected by each lower electrode 410 and is emitted from the upper electrode 460. However, since the layer thickness of the light-emitting

device 401 is extremely small, it can be considered that the light is emitted substantially at the same time.

The use of the transparent electrode, such as an electrode made of ITO, as the upper electrode 460 makes it possible to set an opening ratio indicating a light transmission ratio of the electrode to be substantially equal to the transmittance of the upper electrode 460. In other words, except for the upper electrode 460, there is substantially no portion in which light is attenuated or shielded. Accordingly, the light emitted from the light-emitting layer 450 is less likely to be attenuated or shielded.

In a case where a light-emitting material vulnerable to water, such as an organic EL layer or an inorganic EL layer, is used for the light-emitting layer 450, the light-emitting layer 450 may be desirably sealed to prevent water from penetrating into the light-emitting region 604. As a sealing method a single thin film made of, for example, a silicon oxide, a silicon nitride, and an aluminum oxide is formed, or a sealing film obtained by stacking thin films is formed. As a method for forming the sealing film, a method excellent in coating performance for a structure, such as a step, is desirable. For example, an atomic layer deposition method (ALD method) or the like can be used.

As described above, in a case where the OLED is used as the light source for emitting light to expose the photosensitive drum 103, the upper electrode 460 is formed over the light-emitting layer 450. The term "light-emitting surface" of the substrate 502 refers to the surface of the substrate 502 on which the upper electrode 460 is formed. In other words, the surface of the substrate 502 on which light is emitted from the OLED is defined as the "light-emitting surface".

FIGS. 8A and 8B are diagrams illustrating a portion of a light-emitting surface 502T of the substrate 502 that contacts the holding member 505 according to the present exemplary embodiment. The substrate 502 that also uses the LEDs 503, which is not made of an organic EL, as the light source will be described below by way of example.

FIG. 8A is a diagram illustrating the light-emitting surface 502T of the substrate 502 when the light-emitting surface 502T is viewed in the direction vertical to the light-emitting surface 502T. In FIGS. 8A and 8B, the Y-direction corresponds to the transverse direction of the substrate 502 and the X-direction corresponds to the longitudinal direction of the substrate 502. The LED chips 639 are arranged in the longitudinal direction of the substrate 502.

In this case, regions 502R and 502L indicated by shaded areas in the substrate 502 illustrated in FIG. 8A are regions that contact the holding member 505. As illustrated in FIG. 8A, the region 502R is located on the right end side of the substrate 502 in the transverse direction, and the region 502L is located on the left end side of the substrate 502 in the transverse direction. Each LED chip 639 is provided between the region 502R and the region 502L. Specifically, a leading edge of the extended portion 5050R of the holding member 505 to be described below contacts the right side (one end side) of the light-emitting surface 502T relative to the LED chip 639 in the transverse direction, and a leading edge of the extended portion 5050L of the holding member 505 to be described below contacts the left side (the other end side) of the light-emitting surface 502T relative to the LED chip 639 in the transverse direction. In other words, the "light-emitting surface" is the surface of the substrate 502 on which the photosensitive drum 103 is disposed, or the surface including the LEDs 503 (light-emitting portions). The LEDs 503 are excluded from the region that contacts the holding member 505. That is, the holding member 505 does not contact the LEDs 503.

It is desirable that the width of the substrate 502 in the transverse direction fall within the range from 5 mm to 10 mm. In order to expose the photosensitive drum 103 to light, the LED print head 105 is to be located within close vicinity of the photosensitive drum 103. However, since the charger 104 and the developing unit 641 are present in the vicinity of the photosensitive drum 103, there is a need to increase the size of the image forming apparatus 1 itself to ensure a sufficiently large space. Therefore, it may be desirable to design the width of the substrate 502 to be less than or equal to 10 mm.

On the other hand, there is a need to provide a space for mounting wiring for driving the LED chips 639 and electronic components 950 and 951 to be described below in the substrate 502. Accordingly, even in a case where the width of the substrate 502 in the transverse direction is reduced, the width of about 5 mm is required.

FIG. 8B is a diagram illustrating a mounting surface 502B corresponding to the back surface of the substrate 502. The mounting surface 502B is provided with the electronic components 950 and 951 for driving the LED chips 639. Examples of the electronic components 950 and 951 include one or more driver integrated circuits (ICs). In the present exemplary embodiment, the connector 504 is provided between the electronic components 950 and 951. Power is supplied to the electronic components 950 and 951 through the connector 504. In view of the stability during mass production of the substrate 502 and the stability in the quality of the substrate 502, it is not preferable to provide the electronic components 950 (951) and a wiring pattern near end portions of the substrate 502. Accordingly, it is desirable that a space with a size of about 1 mm to 2 mm be provided in a region from the electronic components 950 (951) and the wiring pattern to the end portions of the substrate 502. Considering all these circumstances, it is desirable that the width of the substrate 502 in the transverse direction be set to more than or equal to 5 mm.

As seen from FIGS. 8A and 8B, the region 502R, which is a region that contacts a leading edge 5051R of the extended portion 5050R, and the region 502L, which is a region that contacts a leading edge 5051L of the extended portion 5050L, partially overlap the electronic components 950 and 951 when the substrate 502 is viewed in the direction vertical to the substrate 502. The width of the substrate 502 is minimized in such a manner, thus preventing the width of the holding member 505 itself from being increased.

(Shape of Holding Member)

FIG. 9 is a diagram illustrating a holding member 1505 of related art. The holding member 1505 includes the base portion 5050B provided with an opening 5052 into which the lens array 506 is inserted, and the extended portions 5050R and 5050L extended from the right and left ends of the base portion 5050B in the direction away from the photosensitive drum 103. The base portion 5050B and the extended portions 5050R (5050L) are integrated together and form a U-shape. Since the holding member 1505 has a U-shape, an opening 5053 is formed on the opposite side of the base portion 5050B. The substrate 502 is inserted from the lower side of the opening 5053, i.e., from the lower side of the holding member 1505 having a U-shape, and is bonded to the inside of the extended portion 5050R and the inside of the extended portion 5050L with an adhesive. The lens array 506 is also bonded to the base portion 5050B with an adhesive in a state where the lens array 506 is inserted into the opening 5052 formed in the base portion 5050B.

As described above, the substrate 502 and the lens array 506 are held by the holding member 1505, so that the LED 503 and an incoming surface 506b of the lens array 506 are opposed to each other. The light emitted from each LED 503 enters the incoming surface 506b and is then emitted to the photosensitive drum 103 from an outgoing surface 506a.

As described above, a conventional holding member 1505 holds a substrate 502 on the inside of a pair of extended portions 5050R (5050L). Accordingly, as illustrated in FIG. 9, an interval W0 between the extended portion 5050R and the extended portion 5050L, or the distance W0 between the pair of extended portions 5050R (5050L) is to be set to be greater than the width of the substrate 502 in the transverse direction of the substrate 502. The substrate 502 cannot be inserted from the opening 5053 without increasing the distance W0 between the pair of extended portions 5050R (5050L) to be greater than the width of the substrate 502. Accordingly, the width of the holding member 1505 is greater than at least the sum of the width of the substrate 502, the width of the extended portion 5050R, and the width of the extended portion 5050L.

Next, a configuration for mounting the holding member 505 and the substrate 502 according to the present exemplary embodiment will be described with reference to FIGS. 10A to 10C.

FIG. 10A is a schematic sectional view of the holding member 505 according to the present exemplary embodiment. This section corresponds to the section of the holding member 505 that is taken along the plane S illustrated in FIG. 3. As illustrated in FIG. 10A, the holding member 505 includes the base portion 5050B provided with the opening 5052, and the extended portions 5050R (5050L) extended from the both ends of the base portion 5050B in the direction away from the photosensitive drum 103. The extended portion 5050R is extended from the right-side end of the base portion 5050B in the direction away from the photosensitive drum 103 and the extended portion 5050L is extended from the left-side end of the base portion 5050B in the direction away from the photosensitive drum 103, thus forming a U-shape. The phrase "direction away from the photosensitive drum 103" used herein indicates the direction opposite to the direction in which light is emitted from each LED 503 in the direction along the optical axis of a certain lens included in the lens array 506. The phrase "the extended portions 5050R (5050L) are extended from the base portion 5050B" does not mean that the holding member 505 is manufactured by extending the extended portions 5050R (5050L) from the base portion 5050B in the manufacturing process of the holding member 505. Metal and resin can be used as a material for the holding member 505. In a case where the holding member 505 is made of metal, a U-shaped holder may be formed by bending a plate, or a U-shaped holder may be formed by cutting a metal block. That is, there is no need to form the holder by preparing the base portion 5050B and then extending the extended portions 5050R (5050L). In a case where resin is used as a material for the holding member 505, the resin material is poured into a prepared mold and is solidified to form the holding member 505. Also, in this case, there is no need to form the holder by solidifying the portion corresponding to the base portion 5050B and then extending the extended portions 5050R (5050L) from the base portion 5050B.

The lens array 506 is inserted into the opening 5052 formed in the base portion 5050B. The extended portion 5050R and the extended portion 5050L are opposed to each other at an interval. Thus, the opening 5053 is formed. The leading edge 5051R of the extended portion 5050R and the

leading edge 5051L of the extended portion 5050L contact the light-emitting surface 502T of the substrate 502. More specifically, the leading edge 5051R of the extended portion 5050R contacts the region 502R of the light-emitting surface 502T of the substrate 502, and the leading edge 5051L of the extended portion 5050L contacts the region 502L of the light-emitting surface 502T of the substrate 502 (see FIGS. 8A and 8B).

FIG. 10B is a diagram illustrating a state where the substrate 502 is bonded to the holding member 505. In this manner, the extended portion 5050R and the substrate 502 are bonded with an adhesive 601 in a state where the leading edge 5051R of the extended portion 5050R is in contact with the light-emitting surface 502T of the substrate 502. Similarly, the extended portion 5050L and the substrate 502 are bonded with the adhesive 601 in a state where the leading edge 5051L of the extended portion 5050L is in contact with the light-emitting surface 502T of the substrate 502. In the present exemplary embodiment, the adhesive 601 is filled in a gap between the leading edge 5051R of the extended portion 5050R and the light-emitting surface 502T of the substrate 502. This state is defined as a state where the leading edge 5051R and the light-emitting surface 502T of the substrate 502 are in contact with each other. As a matter of course, the adhesive 601 need not necessarily be present between the leading edge 5051R and the light-emitting surface 502T of the substrate 502. Specifically, the leading edge 5051R and the light-emitting surface 502T of the substrate 502 may be in direct contact with each other without using an adhesive or the like. For example, a side surface of the extended portion 5050R and the substrate 502 may be bonded with an adhesive.

Moreover, on the left side of the holding member 505, the adhesive 601 is filled in a gap between the leading edge 5051L of the extended portion 5050L and the light-emitting surface 502T of the substrate 502. In the present exemplary embodiment, this state is defined as a state where the leading edge 5051L and the light-emitting surface 502T of the substrate 502 are in contact with each other. As a matter of course, the adhesive 601 need not necessarily be present in the gap between the leading edge 5051L and the light-emitting surface 502T of the substrate 502. Specifically, the leading edge 5051L and the light-emitting surface 502T of the substrate 502 may be in direct contact with each other without using an adhesive or the like. For example, a side surface of the extended portion 5050L and the substrate 502 may be bonded with an adhesive. As the adhesive used in the present exemplary embodiment, an ultraviolet (UV) curable adhesive that is an acrylic adhesive obtained by filling glass filler or the like as a component. The substrate 502 is positioned with respect to the holding member 505 on which the lens array 506 is mounted, while the distance between the lens array 506 and the LEDs 503 on the substrate 502 is adjusted, and the adhesive 601 is filled in the gap between the holding member 505 and the substrate 502 in this state. After that, the adhesive 601 is irradiated with ultraviolet light to fix the substrate 502 to the holding member 505.

As illustrated in FIG. 10B, in this example, a width W1 of the substrate 502 is greater than an interval W2 between a wall surface on the outside of the extended portion 5050R and a side surface on the outside of the extended portion 5050L. As a matter of course, since the width W1 of the substrate 502 is greater than an interval W3 between the extended portion 5050R and the extended portion 5050L, the substrate 502 does not pass through the opening 5053.

Thus, the extended portion 5050R (5050L) and the substrate 502 are arranged so that the leading edge 5051R of the

extended portion **5050R** and the leading edge **5051L** of the extended portion **5050L** are brought into contact with the light-emitting surface **502T** of the substrate **502**. This configuration makes it possible to reduce the width of the holding member **505** as compared with conventional ones.

FIG. 10C is a diagram illustrating a variation of the configuration for mounting the holding member **505** and the substrate **502**. Members including the same functions as those denoted by the same reference symbols used in the description with reference to FIG. 10B are denoted by the same reference symbols. In this example, the interval **W2** between the wall surface on the outside of the extended portion **5050R** and the side surface on the outside of the extended portion **5050L** is greater than the width **W1** of the substrate **502**. Since the width **W1** of the substrate **502** is greater than the interval **W3** between the extended portion **5050R** and the extended portion **5050L**, the substrate **502** does not pass through the opening **5053**.

As illustrated in FIG. 10B, when the width **W1** of the substrate **502** is greater than the interval **W2** between the wall surface on the outside of the extended portion **5050R** and the side surface on the outside of the extended portion **5050L**, the area of a contact portion between the substrate **502** and the leading edge **5051R** of the extended portion **5050R** and the leading edge **5051L** of the extended portion **5050L** can be increased as compared with the configuration illustrated in FIG. 10C. Accordingly, the substrate **502** can be held more stably by the holding member **505**.

On the other hand, in the configuration illustrated in FIG. 10C, the width **W1** of the substrate **502** is minimized, and thus the width of the portion corresponding to the substrate **502** can be further reduced as compared with the configuration illustrated in FIG. 10B. Thus, the configurations illustrated in FIGS. 10B and 10C have their own advantages.

FIGS. 11A to 11C are views each illustrating a portion of the holding member **505** that contacts the substrate **502**. FIG. 11A is a diagram illustrating the holding member **505** as viewed from the lower side. As illustrated in FIG. 11A, a plurality of protrusions **595R** projecting downward is discretely formed at the leading edge of the extended portion **5050R**. Similarly, a plurality of protrusions **595L** projecting downward is discretely formed at the leading edge of the extended portion **5050L**. The protrusions **595R** and the protrusions **595L** will be described in detail below. The light-emitting surface **502T** of the substrate **502** contacts the protrusions **595R** and the protrusions **595L**.

Thus, the leading edges **5051R** (**5051L**) of the extended portions **5050R** (**5050L**) do not contact the entire area of the substrate **502**, but the contact portion is limited, thus increasing the accuracy of the positioning plane and favorably maintaining the flatness of the bonded substrate **502**.

FIG. 11B is an enlarged perspective view of each protrusion **595L**. Since each protrusion **595R** has the same configuration as that of each protrusion **595L**, only the configuration of each protrusion **595L** will now be described. As illustrated in FIG. 11B, the protrusion **595L** formed on the leading edge **5051L** of the extended portion **5050L** has a rectangular parallelepiped shape. In particular, in a case where the holding member **505** is made of resin, for example, only the portion corresponding to the protrusion is formed with higher accuracy than in the other portions, thus considerably improving the positioning accuracy of the substrate **502**.

FIG. 11C is a sectional view of the holding member **505** that is taken along a line vertical to the longitudinal direction of the holding member **505** in such a manner that the line passes through the protrusion **595R** and the protrusion **595L**.

Areas surrounded by broken lines in FIG. 11C indicate a leading edge side of the extended portion **5050R** and a leading edge side of the extended portion **5050L**, respectively. In other words, the phrase “leading edge side of the extended portion **5050R**” indicates the region that is surrounded by a broken line and includes the protrusion **595R**. Similarly, the phrase “leading edge side of the extended portion **5050L**” indicates the region that is surrounded by a broken line and includes the protrusion **595L**.

As illustrated in FIG. 11C, the protrusion **595R** includes three regions, i.e., an outside wall portion **595Ro**, an inside wall portion **595Ri**, and a leading edge **595Rb**. Among these regions, the leading edge **595Rb** contacts the substrate **502**. In this case, the leading edge **595Rb** may correspond to the leading edge of the protrusion **595R** and may also correspond to the leading edge of the extended portion **5050R**. Similarly, the protrusion **595L** includes three regions, i.e., an outside wall portion **595Lo**, an inside wall portion **595Li**, and a leading edge **595Lb**. Among these regions, the leading edge **595Lb** contacts the substrate **502**. In this case, the leading edge **595Lb** may correspond to the leading edge of the protrusion **595L** and may also correspond to the leading edge of the extended portion **5050L**. In other words, the leading edge **595Rb** of the protrusion **595R** corresponds to the leading edge **5051R** of the extended portion **5050R**. The leading edge **595Lb** of the protrusion **595L** corresponds to the leading edge **5051L** of the extended portion **5050L**.

In this manner, in the leading edge of the extended portion **5050R**, a portion where the protrusion **595R** is formed contacts the substrate **502**. On the other hand, in the leading edge of the extended portion **5050R**, a gap corresponding to a projecting amount of the protrusion **595R** is formed between the substrate **502** and the portion where the protrusion **595R** is not formed. By applying an adhesive to the portion corresponding to the gap, the leading edge of the extended portion **5050R** and the substrate **502** are bonded and fixed together.

Similarly, in the leading edge of the extended portion **5050L**, a portion where the protrusion **595L** is formed contacts the substrate **502**. On the other hand, in the leading edge of the extended portion **5050L**, a gap corresponding to a projecting amount of the protrusion **595L** is formed between the substrate **502** and the portion where the protrusion **595L** is not formed. By applying an adhesive to the portion corresponding to the gap, the leading edge of the extended portion **5050L** and the substrate **502** are bonded and fixed together.

Thus, the leading edge of the extended portion **5050R** and the leading edge of the extended portion **5050L** include a portion that contacts the substrate **502** and a portion that does not contact the substrate **502** (adhesive is present). However, as described above, the term “contact” indicates not only a case where the leading edges of the extended portions **5050R** (**5050L**) contact the substrate **502** without involving an adhesive, but also a case where the adhesive is present between the substrate **502** and the leading edges of the extended portions **5050R** (**5050L**).

A second exemplary embodiment of the present disclosure will be described below. In the first exemplary embodiment, the leading edges **5051R** (**5051L**) of the pair of extended portions **5050R** (**5050L**) of the holding member **505** are brought into contact with the light-emitting surface **502T** of the substrate **502**. The second exemplary embodiment illustrates a configuration in which only the leading edge of one of the pair of extended portions is brought into contact with the light-emitting surface **502T** of the substrate **502**.

FIG. 12 is a diagram illustrating a sectional structure of a holding member 901 according to the second exemplary embodiment. Members including the same functions as those described in the first exemplary embodiment are denoted by the same reference symbols.

The holding member 901 according to the second exemplary embodiment includes a base portion 9090B and a pair of extended portions 9090R (9090L) extended from the base portion 9090B, and has a U-shape. As in the holding member 505 according to the first exemplary embodiment, the base portion 9090B is provided with an opening into which the lens array 506 is inserted, and the lens array 506 and the base portion 9090B are bonded with the adhesive 601 in a state where the lens array 506 is inserted into the opening.

The extended portion 9090R is extended from the right-side end of the base portion 9090B in the direction away from the photosensitive drum 103, and the extended portion 9090L is extended from the left-side end of the base portion 9090B in the direction away from the photosensitive drum 103.

As illustrated in FIG. 12, a leading edge 9091R of the extended portion 9090R is in contact with the light-emitting surface 502T of the substrate 502 via the adhesive 601. An inside surface 9090L1 of the extended portion 9090L and the substrate 502 are in contact with each other via the adhesive 601. More specifically, the surface (9090L1) where the substrate 502 is located on the leading edge of the extended portion 9090L is in contact with the left-side end face of the substrate 502. In this manner, the substrate 502 is held by the holding member 901.

As a matter of course, the leading edge of the extended portion 9090L may contact the light-emitting surface 502T of the substrate 502 and the inside (surface where the substrate 502 is disposed on the leading edge of the extended portion 9090R) of the extended portion 9090R may contact the right-side end face of the substrate 502.

FIG. 13 is a view illustrating a configuration on the lower side of the holding member 901 according to the second exemplary embodiment. As illustrated in FIG. 13, a protrusion 596 is formed on the leading edge 9091R of the extended portion 9090R, as in the holding member 505 according to the first exemplary embodiment. A protrusion 597 is formed on the inside surface 9090L1 of the extended portion 9090L. These protrusions are discretely provided in the longitudinal direction of the holding member 901. Thus, the extended portions 9090R (9090L) do not contact the entire area of the substrate 502, but the contact portion is limited, thus increasing the accuracy of the positioning plane and favorably maintain the flatness of the bonded substrate 502.

As described above, according to the configuration described in the present exemplary embodiment, the width between a pair of extended portions constituting the holder of the LED print head can be made smaller than the width of the substrate. Consequently, it is possible to downsize the LED print head in the width direction.

While the present disclosure has been described with reference to exemplary embodiments, it is to be understood that the disclosure is not limited to the disclosed exemplary embodiments. The scope of the following claims is to be accorded the broadest interpretation so as to encompass all such modifications and equivalent structures and functions.

This application claims the benefit of Japanese Patent Application No. 2020-069490, filed Apr. 8, 2020, which is hereby incorporated by reference herein in its entirety.

What is claimed is:

1. A light-emitting element exposure head comprising:
a substrate;
a plurality of light-emitting elements configured to emit light and arranged in a first direction on a surface of the substrate;
a lens array including a plurality of lenses arranged in the first direction, wherein the lens array is configured to condense the light emitted from the plurality of light-emitting elements; and
a holder configured to hold the lens array and having a base portion configured to hold the lens array, a first extending portion extending from the base portion toward the surface of the substrate, and a second extending portion extending from the base portion toward the surface of the substrate, wherein the plurality of light-emitting elements is positioned between the first extending portion and the second extending portion in a second direction which is orthogonal to the first direction and is parallel to the surface of the substrate,
wherein the base portion, the first extending portion, and the second extending portion are positioned between one end of the substrate and the other end of the substrate in the second direction,
wherein a leading edge of the first extending portion in a third direction is bonded to the surface of the substrate, a leading edge of the second extending portion in the third direction is bonded to the surface of the substrate, and the third direction orthogonal to the surface of the substrate, and
wherein, when the holder is viewed along the third direction, a width of the substrate in the second direction is longer than a width of the holder in the second direction.

2. The light-emitting element exposure head according to claim 1, wherein an electronic component configured to drive the plurality of light-emitting elements is provided on a surface of the substrate that is opposite to the surface of the substrate on which the plurality of light-emitting elements is arranged and, when the holder is viewed from the third direction, a contact portion of the holder that contacts the substrate overlaps the electronic component.

3. The light-emitting element exposure head according to claim 1, further comprising a plurality of protrusions projecting in a direction that is opposite to the surface of the substrate on which the plurality of light-emitting elements is arranged,

wherein the plurality of protrusions is discretely formed in the first direction of the holder, and
wherein the holder and the substrate are bonded in a state where the plurality of protrusions is in contact with the substrate.

4. The light-emitting element exposure head according to claim 1, wherein a width of the substrate in a transverse direction falls within a range from 5 mm to 10 mm.

5. The light-emitting element exposure head according to claim 1, wherein the holder is a plate.

6. The light-emitting element exposure head according to claim 1, wherein each of the plurality of light-emitting elements is an organic light-emitting diode.

7. An image forming apparatus comprising:
a photosensitive member configured to be exposed to light by a light-emitting elements exposure head;
a charging unit configured to charge the photosensitive member;
a member charged by the charging unit to light,

21

wherein the light-emitting element exposure head includes:
a substrate,
a plurality of light-emitting elements configured to emit light and arranged in a first direction on a surface of the substrate, 5
a lens array including a plurality of lenses arranged in the first direction, wherein the lens array is configured to condense the light emitted from the plurality of light-emitting elements, and
a holder configured to hold the lens array and having a base portion configured to hold the lens array, a first extending portion extending from the base portion toward the surface of the substrate, and a second extending portion extending from the base portion toward the surface of the substrate, 15
wherein the plurality of light-emitting elements is positioned between the first extending portion and the

22

second extending portion in a second direction which is orthogonal to the first direction and is parallel to the surface of the substrate,
wherein the base portion, the first extending portion, and the second extending portion are positioned between one end of the substrate and the other end of the substrate in the second direction,
wherein a leading edge of the first extending portion is bonded to the surface of the substrate, and a leading edge of the second extending portion is bonded to the surface of the substrate, and
wherein, when the holder is viewed along a third direction orthogonal to the surface of the substrate, a width of the substrate in the second direction is longer than a width of the holder in the second direction; and
a developing unit configured to develop an electrostatic latent image formed on the photosensitive member exposed to light by the light-emitting element exposure head.
